UNITED STATES PATENT OFFICE.

FREDERICK SCHWINN, OF ATTLEBORO, MASSACHUSETTS.

DESIGN FOR A PIERCED SPOON, FORK, OR SIMILAR ARTICLE.

47,740.

Specification for Design.

Patented Aug. 17, 1915.

Application filed April 26, 1915. Serial No. 24,166. Term of patent 3½ years.

To all whom it may concern:

Be it known that I, FREDERICK SCHWINN, a citizen of the United States, residing at Attleboro, in the county of Bristol and State of Massachusetts, have invented a new, original, and ornamental Design for a Pierced Spoon, Fork, or Similar Article, of which the following is a specification, reference being made to the accompanying drawing, forming part thereof.

The figure is a plan view of a pierced spoon, fork or similar article, showing my new design.

I claim:

The ornamental design for a pierced spoon, fork or similar article as shown.

FREDERICK SCHWINN.
